EX

OR D 16,945

UNITED STATES PATENT OFFICE.

JAMES J. McELROY AND ALVIN D. FANCHER, OF BINGHAMTON, NEW YORK.

DESIGN FOR A ROCKING-CHAIR.

UNITED STATES PATENT OFFICE.

JAMES J. McELROY AND ALVIN D. FANCHER, OF BINGHAMTON, NEW YORK.

DESIGN FOR A ROCKING-CHAIR.

SPECIFICATION forming part of Design No. 16,945, dated October 19, 1886.

Application filed November 9, 1885. Serial No. 182,312. Term of patent 3½ years.

To all whom it may concern:

Be it known that we, JAMES J. McELROY and ALVIN D. FANCHER, citizens of the United States, residing at Binghamton, in the county of Broome and State of New York, have invented and produced a new and original Design for Platform Rocking-Chairs; and we do hereby declare the following to be a full, clear, and exact description of the invention, such as will enable others skilled in the art to which it appertains to make and use the same, reference being had to the accompanying photograph, and to letters or figures of reference marked thereon, which form a part of this specification.

Our invention has relation to designs in rocking-chairs; and it consists in a chair having the specific shape and configuration herein shown, whereby a pleasing appearance is produced.

The accompanying photograph fully illustrates the design.

The features of my invention are the shape and ornamentation of the rockers and the rails upon which they rest, the shape and ornamentation of the braces supporting the arms, and the shape of the arms. Upon the base-rails I are placed, in the center and corners, and depending from the upper edge, the floral ornamentation shown in the photograph. Emerging from the point where the rockers A touch, directly over the center design of rails I, are curved lines parallel to the upper edge of said rockers. The rockers A are so formed that a fan-like space is left under the said parallel line at each lower outside corner of the said rocker. These spaces are filled with a floral design corresponding with that upon the

rails I. The brace D leads from the outer and forward end of the rocker A to the rear end 40 of the arm H, forming a compound curve, the lower part of which bulges toward the rocker A and the upper part away from the said rocker. Where it is joined to the rocker the end is enlarged and circular. Rising with an 45 inward curve just above the said enlarged and circular end of the brace D are the supports C. Resting upon and forming a straight line between the upper ends of the braces D and supports C are the arms H. These arms are provided with enlarged and circular ends corresponding to those of the braces D. All the outer faces of the parts here described are marked with parallel and longitudinal lines, substantially as shown in photograph. 55

What we claim is--

In a design for rocking-chairs, the body thereof, consisting of a curved rocker having enlarged fan-like ends, a brace having a compound curve and an enlarged circular end 60 where it joins said rocker, a straight arm resting upon said brace and extending forward, and having a circular end corresponding to the end of the said brace, and a curved support, curved inwardly and joining the circular ends of the said arm and brace, all having the shape and ornamentation shown and described. 65

In testimony whereof we affix our signatures in presence of two witnesses.

JAMES J. McELROY.
ALVIN D. FANCHER.

Witnesses:

A. L. PINE,
A. S. BROWN.
